DESIGN FOR A CIGARETTE HOLDER OR SIMILAR ARTICLE

Claudia M. Gemmill, York, Pa.

Application May 6, 1939, Serial No. 84,849

Term of patent 14 years

To all whom it may concern:

Be it known that I, Claudia M. Gemmill, a citizen of the United States of America, residing at York, in the county of York and State of Pennsylvania, have invented a new, original, and ornamental Design for a Cigarette Holder or Similar Article, of which the following is a specification, reference being had to the accompanying drawing, forming part thereof, wherein

Fig. 2 is a side elevation thereof;

Fig. 3 is a front elevation thereof; and

Fig. 4 is a top plan view.

I claim:

The ornamental design for a cigarette holder or similar article, as shown.

CLAUDIA M. GEMMILL.
